UNITED STATES PATENT OFFICE.

WALTER CLYDE JONES AND GEORGE ELLIOT PERRY, OF CHICAGO,
ILLINOIS; SAID PERRY ASSIGNOR TO PERRY TIME STAMP COM-
PANY, OF CHICAGO, ILLINOIS, A CORPORATION OF ILLINOIS.

TIME-STAMP.

No. 852,563.

Specification of Letters Patent.

Patented May 7, 1907.

Application filed June 16, 1904. Serial No. 212,834.

To all whom it may concern:

Be it known that we, WALTER CLYDE JONES and GEORGE ELLIOT PERRY, citizens of the United States, residing at Chicago, in the county of Cook and State of Illinois, have invented new and useful Improvements in Time-Stamp, of which the following is a full, clear, concise, and exact description, reference being had to the accompanying drawing, forming a part of this specification.

Our invention relates to improvements in time stamps, and more particularly to portable stamps in which the motor for actuating the impression mechanism is carried with the stamp.

The object of our invention is the provision of improved inking means for time stamps. Our invention relates to that class of time stamps in which the impression means directly engages the surface to be impressed. In accordance with our invention we provide an inking pad adapted to ink the impression surface, the pad being provided with revoluble inking parts adapted to coact with and to accommodate the movement of the time controlled elements of the impression means.

We have illustrated the preferred form of our invention in the accompanying drawings in which:

Figure 1 is a side elevation of the stamp, taken on the line 1—1 of Fig. 2; Fig. 2 is a front elevation of the stamp taken on the line 2—2 of Fig. 1 and having certain parts broken away; Figs. 3 and 4 are detail views of the resilient mounting for the motor; Fig. 5 is a sectional view taken on the line 5—5 of Fig. 2; Fig. 6 is a sectional view on the line 6—6 of Fig. 5; Fig. 7 is a view taken on the line 7—7 of Fig. 5; and Fig. 8 is a face view of the impression mechanism.

In the preferred construction of our invention, we provide a suitable supporting frame having end pieces 1, to the top of which is secured a table 2, having side walls 3, formed integral therewith, which with the end pieces 1 and the table 2, form a box or casing for the motor 4. The bottom portion or legs 5 of the end pieces 1 constitute gage parts which are adapted to engage the surface to be impressed, and adjust the impression mechanism relatively to said surface to aid in securing a clear and legible impression.

Any desired self contained and self regulating motor mechanism may be used, and the form thereof illustrated in the drawing comprises a clock train having the usual main spring 6 and winding stem 7. The motor mechanism is preferably mounted in any suitable manner between plates 8 and 9, arranged within the casing, screws or bolts 10 being provided for connecting said plates together. Resiliently mounted upon the bolts 10 are bars or rods 11, adapted to move longitudinally upon said pins, and normally held in position thereon by means of small coiled springs 12. A pair of said springs is provided upon each of the pins, one of the pair being disposed above, and the other of the pair below the contiguous ends of the bars 11. Secured at each end of the casing to the outer plate 3, are small springs 13. These springs are preferably formed of stamped metal, and have centrally disposed extended portions formed thereon provided with a recess adapted to receive the bars 11 and support the motor mechanism in position. The end springs 14 are provided with centrally disposed flanges 15, which fit over the bars 11. The springs also have formed therein a small aperture 16, which is adapted to receive a pin 17, carried upon the bars 11, which aids in retaining the springs in position thereon. The extended ends of the springs 14 are broadened to afford a wider bearing surface, and are adapted to rest against the inner face of the supporting plates 1.

In mounting the motor mechanism in position within the casing, the springs 14 are placed in position upon the rods 11, the motor mechanism is then inserted in position with the extended ends of said springs resting against the inner faces of the plates 1. The extended portions or flanges carried by the springs 13 are then sprung to position upon their respective bars 11. It will be seen that the coiled springs 12 effectively cushion the motor mechanism in a perpendicular plane, and the springs 13 and 14 effectively cushion the motor mechanism in a horizontal plane.

It will be understood that the particular disposition of the springs above described with reference to the motor mechanism, and the bars 11, is not essential to our invention, and other resilient means may be provided,

or the springs differently arranged with reference to their several co-acting parts without departing from the spirit of our invention.

5 Fixedly mounted upon the table 2, is a tube 15^a adapted to telescope within a handle 16^a against the power of a coiled spring 17^a when an impression is made. Secured to the handle 16^a is a yoke or inverted U-shaped 10 plate 18, the free ends of which pass through apertures formed in the table 2 and carrying the printing mechanism of the stamp, which is preferably secured to the yoke by a pin 19, passing through the printing mechanism and 15 engaging the ends of the yoke. The printing mechanism is preferably carried by plates 20 and 21 which are secured together in any suitable manner as by screws or bolts 22. The ends of the plate are upturned as shown 20 in Fig. 2 and are connected by the pin 19 with the yoke 18, the upper end of said extending portion being formed with projections which fit on either side of the yoke to prevent lateral movement of the plates. The 25 printing mechanism comprises revolute dies 23 which indicate the time upon dials 24 fixedly mounted upon the plate 21. Any desired symbol may be mounted upon the portion of the plate not occupied by the dials 30 and their cooperating revolute dies to constitute the operative face of the impression mechanism. Three revolute dies are preferably provided as shown in Fig. 8, for the purpose of printing the hour, minute and the 35 meridian.

35 While we have illustrated our invention with reference to revolute dies and dials for indicating the time, it will be understood that other revolute printing mechanism 40 may be adopted in lieu of said dies and dials, without departing from the spirit of our invention.

Carried upon an arbor 25 of the motor mechanism is a small wheel 26 having a pin 45 27, mounted eccentrically of its axis, which is adapted to engage in radial slots 29 formed in a wheel 28 carried by the arbor of one of the revolute impression dies 23, and thereby 50 operate the impression mechanism. The upper portion of the slots 29 are beveled as shown, whereby when the two wheels have 55 been disconnected in making an impression and the wheel 28 is again connected to the motor mechanism, this wheel may be moved to properly receive the pin 27, and synchronize the two mechanisms. The provision of the radial grooves 29 in the wheel 28 permits a movement of the motor mechanism upon its resilient mounting when the 60 impression mechanism is in engagement with the motor without affecting the impression mechanism.

It is necessary that the revolute dies move relatively to each other in order at all times

to have the dies for printing the minute and 65 the hour in proper position. This movement of the dies is accomplished by means of suitable gearing 30 disposed between the plates 20 and 21, and driven by the wheel 31 mounted upon the arbor of the printing 70 wheel 28. The dies 23 are preferably formed of rubber or other resilient material, and are disposed within cups 32 journaled to the gearing 30.

An inking pad 33 is provided for inking the 75 operative face of the printing mechanism, and comprises two sections which rest normally in engagement with the operative face of the printing mechanism, and which are adapted to be moved from engagement therewith as the stamp is operated in making an impression. Carried by the inking pads 33 are revolute inking pads 34 which align with the revolute printing dies 23 when the pad is in engagement with the printing mechanism, 80 and which normally rest in engagement and revolve with the dies 23. The portion 33 of the pad which inks the operative face of the stationarily mounted printing mechanism is carried by a supporting plate 35, the ends of 85 which are upturned, as shown in Fig. 5. A thin metal stip 37 is disposed between the bottom of the supporting plate and the pad and has upwardly extending flanges formed thereon which project through openings in 90 the pad, and are provided with rims 38 to engage the revolute pads 34 and retain the same in position within the flanges. Depressions 39 are provided in the plate 35, 95 which accommodate the V-shaped spurs 40 extending from the bottom of the cups containing the revolute inking pads 34 whereby 100 a substantially frictionless bearing for said cups is provided.

The particular arrangement of the revolute pads 34 upon the plate 35 and the retaining rim 38 and bearing 40 are not essential to our invention, as other forms of revolute pads may be provided upon the supporting plate 35 without departing from the spirit of 110 our invention.

The supporting plates 35 are hinged or pivoted to swing out of engagement with the impression mechanism, and out of the path thereof, when the stamp is operated to make 115 an impression. This is accomplished by means of rods or arms 41 and 43, one end of the rods 41 is suitably pivoted to the contiguous ends of the supporting plates 35, and the other end thereof is pivoted to the casing 3. 120 Pivoted to the opposite ends of the supporting plates 35 are links 42 which are suitably pivoted at their opposite ends to the plate or casing 3. The pads are held in normal position by links 43, one end thereof being suitably pivoted to the yoke 18, and the other end pivoted to the rods 41. An offset 44 is 125 preferably provided in the rods 41 to prevent

the end of the link 42 from interfering with the movement thereof when the stamp is operated in making an impression.

The drop pads carried by the plates 35 normally rest in engagement with the operative face of the impression mechanism. When the handle 16^a is depressed in making an impression, however, the rods or arms 43 cause the outer ends of the arms 41 to move in an arc of a circle, depressing the pads and moving the same out of engagement with the operative face of the impression mechanism and to the position shown in dotted lines in Fig. 1. It will be noted that the corners of the drop pads to which the links 42 and rods 41 are pivoted move simultaneously when the stamp is operated in making an impression, thus permitting the pads to partake of a direct or right line movement in leaving the face of the impression mechanism, and that after the pads are disengaged from the face of the impression mechanism, they are carried in an arc of a circle out of the path of the impression mechanism. This direct or right line movement of the pads in leaving the face of the impression mechanism, prevents the surface of the pads from dragging on the faces of the revoluble impression parts and the stationary impression parts of the impression mechanism. The impression mechanism pivoted to the yoke 18 by the rod 19, is carried into engagement with the face of the article to be stamped, against the power of the spring 17^a, and said spring returns the parts to their normal positions, after the handle has been released.

While we have described our invention with particular reference to the details of construction, we are aware that many changes may be made therein without departing from the spirit of our invention, and we do not wish to limit ourselves to the particular details of construction above described, further than is defined in the appended claims.

Having described our invention what we claim as new and desire to secure by Letters Patent is:

1. In a time stamp, the combination with impression mechanism having moving time controlled parts, of a horologic motor for driving said parts, and a revoluble inking pad for inking said parts disposed between the face of said mechanism and the surface to be impressed and adapted to be carried out of the path of said mechanism when an impression is made.

2. In a time stamp, the combination with impression mechanism having moving time controlled parts, of a horologic motor for driving said parts, and a revoluble inking pad for inking said parts disposed between the face of said mechanism and the surface to be impressed, said pad being adapted to rest normally in engagement with and rotate

with said parts, and being adapted to be carried out of the path of said mechanism when an impression is made.

3. In a time stamp, the combination with impression mechanism having moving time controlled parts, of a horologic motor for driving said parts, a revoluble inking pad for inking said parts disposed between the face of said mechanism and the surface to be impressed, said impression mechanism being movable to make an impression, and means for carrying said pad out of the path of the impression mechanism when an impression is made.

4. In a time stamp, the combination with impression mechanism having a plurality of moving time controlled parts, said mechanism being movable to make an impression, of a horologic motor for driving said parts, and a plurality of revoluble inking pads for inking said parts disposed between the face of said mechanism and the surface to be impressed and adapted to be carried out of the path of said impression mechanism when an impression is made.

5. In a time stamp, the combination with revoluble dies having means for varying the character of the impression adapted to be made thereby, a horologic motor for driving said dies, revoluble inking pads for said dies, said pads being disposed between said dies and the surface to be impressed and being adapted to rest normally in engagement with the operative faces of said dies, and means for removing said pads from engagement with said dies when an impression is made.

6. In a time stamp, the combination with impression mechanism having moving time controlled parts, said mechanism being movable to make an impression, of a horologic motor for driving said parts, and a drop pad for inking said parts, said pad being adapted to rest normally in engagement with and rotate with said parts, and being adapted to be carried out of the path of the impression mechanism when an impression is made.

7. In a time stamp, the combination with impression mechanism having stationary impression parts and moving time controlled impression parts, of a horologic motor for driving said moving parts, a drop pad for inking said stationary impression parts, and a revoluble pad carried by said drop pad for inking said moving parts.

8. In a time stamp, the combination with impression mechanism having stationary impression parts and moving time controlled impression parts, of a horologic motor for driving said moving parts, a drop pad for inking said stationary impression parts, a revoluble pad carried by said drop pad for inking said moving parts, said impression mechanism being movable to make an impression, and means for carrying said pads out of the path of the impression mechanism

when the stamp is operated to make an impression.

9. In a time stamp, the combination with 5 impression mechanism having stationary impression parts and moving time controlled impression parts, of a horologic motor for driving said moving parts, a pair of drop pads for inking said stationary impression parts, a revolute pad carried by said drop 10 pads for inking said moving parts, said impression mechanism being movable to make an impression, and means for carrying said pads out of the path of the impression mechanism when the stamp is operated to make an 15 impression.

10. In a time stamp, the combination with 20 impression mechanism having stationary impression parts and moving time controlled impression parts, of a horologic motor for driving said moving parts, a drop pad for inking said stationary impression parts, a plurality of revolute inking pads for inking said moving time controlled parts carried by said drop pad, said pads being adapted to rest 25 normally in engagement with said impression mechanism, and means for carrying said pads out of the path of the impression mechanism when an impression is made.

11. In a time stamp, the combination with 30 a stationary frame having gage parts adapted to engage the surface to be impressed, of a second frame, revolute impression mechanism carried by said second frame, said second frame being movable to make an impression, 35 a horologic motor for operating said impression mechanism, a third frame, and revolute inking pads carried by said last mentioned frame, said pads being adapted to rest normally in engagement with said revolute impression mechanism and to move out of the 40 path of said mechanism when an impression is made.

12. In a time stamp, the combination with 45 a stationary frame having gage parts adapted to engage the surface to be impressed, of a second frame, revolute impression mechanism carried by said second frame, said second frame being movable to make an impression, a horologic motor for operating said impression 50 mechanism, a third frame, revolute inking pads carried by said last mentioned frame, said pads being adapted to rest normally in engagement with said revolute impression mechanism, and means adapted to 55 carry said revolute inking pads out of the path of said impression mechanism when an impression is made.

13. In a time stamp, the combination with 60 a stationary frame having gage parts adapted to engage the surface to be stamped, of a second frame, revolute impression mechanism carried by said second frame, stationary impression mechanism also carried by said second frame, said second frame being movable to make an impression, a horologic mo- 65

tor for driving said revolute impression mechanism, a third frame, revolute inking pads carried by said last mentioned frame, and a stationary inking pad also carried by said last mentioned frame, said pads being 70 adapted to rest normally in engagement with the operative faces of said impression mechanisms and being adapted to be carried out of the path of said mechanisms when an impression is made. 75

14. In a time stamp, the combination with a stationary frame, said frame having gage parts adapted to engage the surface to be impressed, of a second frame, revolute impression mechanism carried by said second frame, said second frame being movable to make an impression, a handle for operating said second frame, a third frame, revolute inking pads carried by said last mentioned frame, and bars or rods pivoted to said stationary frame, to said third frame and to said handle, said pads being adapted to rest normally in engagement with said revolute impression mechanism, said rods being adapted to carry said pads from engagement with 90 said impression mechanism when the same is operated to make an impression.

15. In a time stamp, the combination with impression mechanism having moving time controlled parts, of a revolute inking pad 95 for inking said parts, said pad being adapted to rest normally in engagement with said parts, a horologic motor for driving said moving parts, and a resilient mounting for said motor. 100

16. In a time stamp, the combination with suitable impression mechanism, of means for varying the character of the impression adapted to be made thereby, a horologic motor for operating said means, an automatically operated inking pad adapted to rest normally in engagement with said impression mechanism, and adapted to partake of a right line movement in leaving the face of said impression mechanism when an impression is 110 made.

17. In a time stamp, the combination with a suitable impression mechanism, of means for varying the character of the impression adapted to be made thereby, a horologic 115 motor for operating said means, an inking pad adapted to rest normally in engagement with the face of said impression mechanism, the four corners of said pad being adapted to move simultaneously in a right line movement in leaving the face of the impression mechanism when an impression is made, and means for carrying said pad out of the path of the impression mechanism after said pad has been carried from engagement therewith. 120

18. In a time stamp, the combination with a support, of an impression mechanism having means for varying the character of the impression adapted to be made thereby, a horologic motor for driving said means, and 130

an inking pad permanently carried by said support and adapted to rest normally in engagement with the face of said impression mechanism, and partake of a right line movement in leaving the face of the impression mechanism when an impression is made.

19. In a time stamp, the combination with impression mechanism having means for varying the character of the impression adapted to be made thereby, of a horologic motor for driving said means, an inking pad adapted to rest normally in engagement with the face of said impression mechanism, said pad being adapted to partake of a right line movement in leaving the face of said impression mechanism, and means actuated by the movement of the stamp in making an impression for carrying said pad out of the path of the impression mechanism after said pad has been disengaged therefrom.

20. In a time stamp, the combination with

impression mechanism having means for varying the character of the impression adapted to be made thereby, of a horologic motor for driving said means, an inking pad adapted to rest normally in engagement with the face of said impression mechanism links and rods pivoted to said pad, said rods and said links imparting a right line movement to said pad in leaving the face of the impression mechanism and carrying said pad out of the path of the impression mechanism when the stamp is operated to make an impression.

In witness whereof, we have hereunto subscribed our names in the presence of two witnesses.
